UNITED STATES PATENT OFFICE.

BERNARD I. McELROY, OF PROVIDENCE, RHODE ISLAND.

DESIGN FOR A BUTTON.

SPECIFICATION forming part of Design No. 26,143, dated October 6, 1896.

Application filed July 21, 1896. Serial No. 600,066. Term of patent 7 years.

To all whom it may concern:

Be it known that I, BERNARD I. McELROY, a citizen of the United States, residing at Providence, in the county of Providence and 5 State of Rhode Island, have invented and produced a new and original Design for Buttons; and I do hereby declare the following to be a full, clear, and exact description of the same, reference being had to the accompanying 10 drawings, forming a part thereof.

My invention consists in a button having the representation of a man's head and bust in elevation upon its face and a shank consisting of a curved tube connected with an opening through the button at the man's mouth. 15

In the accompanying drawings, illustrating my new design, Figure 1 is a front view, and Fig. 2 is a sectional view.

The leading feature of my design consists 20 of the representation of a man's head and bust raised above the face of the button and a hollow shank projecting from the back of the button and extending outwardly and downwardly at an angle beyond the periphery 25 of the button, said shank having no base.

In the drawings, A denotes the face of the

button, having the representation of a man's face B in elevation above the plane of the button-face and the representation of a man's bust C farther raised above the button-face 30 and extending to the periphery of the button, where the greatest elevation is given the bust.

The back D of the button has a hollow shank or tubular stem E curved outwardly from the back of the button and downwardly 35 below the periphery of the button and communicates with an aperture F, extending through the mouth of the representation. This stem E is adapted to be inserted through a buttonhole and have connected with it a 40 rubber tube carrying a bulb filled with perfume or other liquid to be discharged through the mouth of the figure.

What I claim is—

The design for a button herein shown and 45 described.

In testimony whereof I affix my signature in presence of two witnesses.

BERNARD I. McELROY.

Witnesses:

JOHN C. QUINN,
CHARLES H. PAGE.
